UNITED STATES PATENT OFFICE

WILHELM KUNST, OF BARMEN, GERMANY, ASSIGNOR TO HEINRICH ESSER, OF HILDEN, GERMANY

MANUFACTURE OF SEAMLESS TUBES

Application filed April 4, 1927, Serial No. 181,010, and in Germany January 17, 1927.

My invention relates to the manufacture of seamless tubes by rolling and has for its object to simplify and expedite the production.

5 It has already been proposed to produce seamless tubes from a tubular blank by rolling it out upon a roughing and a cogging mill and finishing rolls, a reducing mill being provided between the cogging and the finishing trains in which the billet or ingot coming from the cogging mill is reduced in diameter. In this way a large number of passes can be saved in the finishing rolls.

The present invention differs fundamentally from the foregoing in that the thick walled tubular blank is reduced to a thinner wall in a piercing mill, the ingot being then reduced to the desired diameter in a reducing rolling mill, and then rolled out to the final 20 wall-thickness in a two-high rolling mill.

In the drawings affixed to this specification and forming part thereof, the invention is illustrated diagrammatically by way of example.

25 In the drawings

Fig. 1 shows a piercing mill 1, and mandrel 2 in the course of reducing the wall thickness of a thickwalled tubular blank 3,

30 Fig. 2 illustrating a reducing rolling mill 4 and the tubular workpiece 5 whose outer diameter is reduced to the extent finally desired.

Fig. 3 shows a two high mill 6 and the workpiece 7 in the course of having its wall thickness further reduced, the workpiece being at the same time stretched to assume its final length without its outer diameter being changed.

35 Obviously a blank of predetermined great wall-thickness can thus be converted into a tube of any inferior wall-thickness by adding or removing the respective passes and mandrels.

40 In this way not only is the process of production shortened and simplified, but the construction of the whole plant for carrying it out is also simplified. In the place of the roughing and cogging mills a piercing mill is employed, whereby a whole rolling set 50 is saved. Reheating of the blank before the

finishing rolling in the two-high rolling mill is not necessary, because the blank leaves the piercing mill considerably hotter than it emerged from the cogging mill.

I wish it to be understood that I do not desire to be limited to the exact details of construction shown and described for obvious modifications will occur to a person skilled in the art.

55 I claim:—

1. The process of producing seamless tubes by rolling, comprising reducing the wall thickness of a comparatively thick-walled tubular blank, thereafter reducing the diameter of the said blank to the final diameter and thereafter reducing the wall thickness of said blank to the final thickness.

60 2. The process of producing seamless tubes by rolling, comprising reducing the wall thickness of a comparatively thick-walled tubular blank in a piercing mill, thereafter reducing the diameter of the said blank to the final diameter in a reducing mill and thereafter reducing the wall-thickness of said blank to the final thickness in a two- 65 high rolling mill.

70 In testimony whereof I affix my signature.

WILHELM KUNST.
